LIFTING DEVICE FOR BEDS

Fred E. Hollis, Pittsburgh, Pa.

Application May 1, 1945, Serial No. 591,307

3 Claims. (Cl. 5—81)

1

This invention relates to new and useful improvements in lifting aids for bedridden hospital patients and the like, and it is among the objects thereof to provide a grip support mounted on a portable stand and which is out of the patient's way when not in use.

It is a further object of the invention to provide a portable gripping support that is always within the reach of the patient to be movable in the proper position in register with the patient, in which the gripping member shall be self-interlocking with the support when gripped by the patient.

These and other objects of the invention will become more apparent from a consideration of the accompanying drawing constituting a part hereof, in which like reference characters designate like parts, and in which

Fig. 1 is a view in perspective of a movable grip on a portable support embodying the principles of this invention; and

Fig. 2 an enlarged detail of a portion of the grip and clamping member for securely locking the same in any position on a support.

In the drawing the numeral 1 designates a pair of standards supported on feet 2 which are spaced to distribute the load on the support on a four-point contact with the floor to guard against tilting or other movements. The standards 1 are provided with T-connections 3 for supporting a tube 4 which is secured in position by set screws 5. A grip having a handle member 6 on a yoke 7 is slidably mounted on the tube 4 by a U-shaped bracket 8. As shown in the large view of Fig. 2 the yoke members 7 are fastened to a wedge block 9 that is pivotally mounted on a sleeve 10 which constitutes a pivot bearing and which is journaled on saddle 8. A bolt or screw 11 passing through the pivot bearing 10 secures the block 9 in saddle

8. The handle parts 7 are secured to block 9 by a bolt passing through opening 12. The load is always on the sleeve 10 and the bolt 12 is free to turn in the bore of the sleeve 10. The block 9 is provided with a curved concave surface 13, the curvature of which is the same radius as the tube 4 so as to effect intimate surface contact with the tube when in engagement therewith, and to provide a clearance for sliding the block 9 longitudinally of the tube 4 when the handle 6 is tilted.

The block 9 is preferably made of aluminum and a pair of aluminum runners 14 are secured in the U-shaped bracket 8 for engaging the upper surface of the tube 4. The use of the aluminum block and runners eliminates wear from sliding contact and assures a firm gripping action when

2

the clamp block 9 is in engagement with the tube 4.

The handle 6 is biased by a coil spring 15 to be normally in the horizontal position shown in the dotted lines, which position is assumed when the handle 6 is released. The entire handle unit is movable on the tube 4 by means of a rope and pulley arrangement which consists of brackets 16 and 17 having shive wheels 18 and 19 mounted on adjustable brackets therein. The rope 20 passing over the pulleys is secured at 21 and 22 to the U-shaped bracket 8, a guide 23 being provided to prevent tangling of the rope. By means of the cord 20 the patient, who may be in a given position in a bed, can, by pulling the cord, move the gripping unit in overhead alignment where he can reach the grip or handle 6 and pull it down. When in a vertical position as shown in Fig. 1, the weight of the patient's body or the pulling force 20 causes the cam block 9 to intimately engage the tube 4 and lock the gripping unit in position thereon. The patient may then readily adjust his position in the bed or pull himself to an upright position without any danger of the grip slipping out of position or without danger of tilting or moving the grip support.

The supporting structure may be used to facilitate the handling of hospital equipment such as mounting of fluid containers 24 on slideable brackets 25 or the mounting of a weight support 26 which by set screws 27 is adjustable to any desired vertical position relative to the support.

It is evident from the foregoing description of the invention that lifting grips for hospital beds made in accordance therewith assure safe movement of the patient and are available for use at all times without aid, and when not in use such a grip does not interfere with the normal use of a hospital bed.

Although one embodiment of the invention has been herein illustrated and described, it will be evident to those skilled in the art that various modifications may be made in the details of construction without departing from the principles herein set forth.

I claim:

1. In a lifting device for beds, a support comprising an overhead track, a bracket mounted for sliding movement on said track, a bearing sleeve 50 mounted for pivotal movement in said bracket, a cam block journaled on said bearing sleeve, said bearing sleeve being secured to the bracket by a bolt extending through the walls of the bracket, a handle member secured to the cam block, said cam block having a cam surface

which in the lowered position of the handle engages the track to lock the bracket against movement on the track, and said cam block having a track engaging surface complementary in shape with the surface of the track with which it contacts in its locking position.

2. In a lifting device for beds, a support comprising a horizontally disposed overhead track, a U-shaped bracket mounted for sliding movement on said track with the base of the U resting on the track, a bearing sleeve extending through the walls of the U-shaped bracket for pivotal movement therein, a bolt extending through the bearing sleeve for holding the sleeve in the bracket, a cam block pivotally mounted on the bearing sleeve, and a handle or grip fastened to the cam block, the cam block having a cam surface for engaging the underside of the overhead track when the handle is in the down position, such that the weight on the handle increasingly locks the cam block and track against movement, said cam surface being of a contour complementary to the under surface of the track which it engages.

3. In a lifting device for beds, a support comprising a horizontally disposed overhead track, a U-shaped bracket mounted for sliding movement on said track with the base of the U resting on the track, a bearing sleeve extending

5 through the walls of the U-shaped bracket for pivotal movement therein, a bolt extending through the bearing sleeve for holding the sleeve in the bracket, a cam block pivotally mounted on the bearing sleeve, a handle or grip fastened to the cam block, the cam block having a cam surface for engaging the underside of the overhead track when the handle is in the down position, such that the weight on the handle increasingly locks the cam block and track against movement, said cam surface being of a contour complementary to the under surface of the track which it engages, and means normally biasing said handle in the direction to effect disengagement of the cam surface with the track when not in use.
